Primary Examiner—M. N. Pandozzi[57] **CLAIM**

The ornamental design for a novelty golf club with four compartments for transporting liquids therein, as shown and described.

DESCRIPTION

FIG. 1 is a front elevational view of the novelty golf club with four compartments for transporting liquids therein showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is a sectional view taken vertically through the mid-plane of the device at line 7—7 of FIG. 5.

The novelty golf club with four compartments for transporting liquids therein is broken away in two places in FIGS. 1, 2, 3, 4, and 7 to show indeterminate length.
